UNITED STATES PATENT OFFICE.

JOHN N. RUFFIN, OF NEW YORK, N. Y.

CALORIC ENGINE.

1,035,474.

Specification of Letters Patent. Patented Aug. 13, 1912.

Application filed December 4, 1911. Serial No. 663,950.

To all whom it may concern:

Be it known that I, JOHN N. RUFFIN, a citizen of the United States, residing at New York, in the county of New York and 5 State of New York, have invented certain new and useful Improvements in Caloric Engines; and I do hereby declare the following to be a full, clear, and exact description of the invention, such as will enable 10 others skilled in the art to which it appertains to make and use the same, reference being had to the accompanying drawings, and to letters or figures of reference marked thereon, which form a part of this specification. 15

This invention relates to improvements in "caloric engines," and more particularly to the means employed for generating the heat.

20 The object of the invention is to provide a horizontally disposed caloric engine with a cook stove or range, having certain characteristics, whereby I am enabled to provide economical power for domestic purposes for running small plants etc.

25 The invention also relates to the specific details of construction and arrangement of parts to be hereinafter described and particularly pointed out in the claim.

30 In the accompanying drawings: Figure 1 is a front elevation of my improved apparatus. Fig. 2 is a section on the line $x-x$ of Fig. 1. Fig. 3 is a horizontal section on the line $y-y$ of Fig. 1.

35 Numeral 1 indicates a cook stove comprising a fire pot 2, rear flues 3, near the top and bottom of the fire pot, and an exit flue 4 with which the flues 3 communicate. A side flue 5 also communicates with the fire 40 pot 2 near the top thereof and passes around the oven 7^a, and performs a dual function. The flue 5 communicates with an exit flue 7, connected to the exit flue 4 by a branch flue 8. The exit flue 7 is provided with a 45 damper 9, while the branch exit flue 8, is provided with a damper 10. The top of the casing is formed with a seat 11 which receives the flanges 12^a of a cup shape casting 12, which depends in the fire pot 2, the 50 bottom of said casting being concavo-convex to afford strength, and at the same time provide a pocket for the flame from the fuel in the fire pot. The bottom of the casting 12 terminates substantially mid-way between the flues 3 to insure of the flame pass-

ing around the side walls of the casting to effectually heat the air.

Mounted on the top of the casing 1, is a horizontal caloric engine 15. This engine comprises a casing 16 formed with a vertical 60 depending hollow portion 17, provided at its bottom with a flange 18 which is bolted to the top of the stove casing 1 and registers with the casting 12. The hollow portion 17 communicates with a port 19 leading to 65 a cylinder 20 on the casing 16. Operating in the cylinder 20 is a piston 21 connected with a piston rod, which in turn is connected with a link 22. The link is pivoted to a rocking lever 23, having pivoted there- 70 to a link 24, connected with a piston rod 25, extending from a piston 26, operating in the hollow portion 17 and the cup shape casting 12. The engine is provided with the usual fly wheel, air inlet valve and other 75 accessories which are necessary in an engine of this type, but form no part of my present invention.

When the parts are assembled as described, a fire is started in the range and 80 the heat in passing to the flues heats the air in the cup shape casting 17, and then expands the same, thereby raising piston 26, and dissipating the heated air in the port 19 and behind the piston 21, and as a consequence actuates said piston. To control the engine, the dampers 9 and 10 are operated for instance while the stove is used for baking purposes, damper 9 is opened and the damper 10 is closed, causing the ignited 85 gases to pass to the exit flue 7 and escaping to a large degree past the cup shape casting 12. However, when the damper 10 is opened and damper 9 is closed, the ignited gases are caused to pass directly through 90 the flues 3-3, and in so doing contact directly with the walls of the casting 12 and effectually heat the air therein, at which time the most effective force of the engine 95 is obtained. By this system of dampers and the construction and location of the cup shape casting a simple and effective means is afforded for combining all the salient and practical features of a cook stove, as well as means for controlling the engine and affording efficient and economical means for deriving the necessary power for domestic 100 purposes.

105 By constructing the cup shape casting as described, and the vertical flanged portion 110

of the casing 15, the latter holds the former in position, and avoids the expense and labor of separate fastening means, which is vital in an apparatus of the type described.

5 I have specifically defined a horizontally disposed caloric engine for the very obvious reason that it is of the utmost importance from a standpoint of economy in space as it is my purpose to utilize my improvements for domestic purposes, obviously the importance of utilizing all availing space is quite essential.

10 What I claim is:

15 In combination a caloric engine comprising a casing provided with a port and a vertical cylindrical hollow portion having a flange at its lower end, said hollow portion communicating with the port and a cylinder on the casing and communicating with 20 the port, a vertically operated piston in the vertical hollow portion, a casing having a fire pot, rear flues communicating with the top and bottom of the fire pot, an exit flue communicating with the said rear flues, a

damper in said flue, a side flue communicating with the fire pot near the top thereof, an exit flue communicating with the latter side flue, a damper in the latter exit flue, the casing having in its top an opening, a cup shape casting having a flange at its upper 25 end and fitting in the opening in the top of the casing, the bottom of the casting terminating substantially mid-way between the rear flues and below the plane of the side flue, and means securing the flange of the 30 vertical hollow portion of the engine casing to the top of the casing and for holding the cup shape casting in position, said vertical hollow portion, and the cup shape casting forming a cylinder to receive the vertical 35 piston of the engine.

40 In testimony whereof I have signed my name to this specification in the presence of two subscribing witnesses.

JOHN N. RUFFIN.
